UNITED STATES PATENT OFFICE

EDWARD M. FREELAND, OF STEUBENVILLE, OHIO, AND FRANK MCGOUGH, OF FOLLANSBEE, WEST VIRGINIA, ASSIGNORS TO FOLLANSBEE BROTHERS COMPANY, OF PITTSBURGH, PENNSYLVANIA, A CORPORATION OF PENNSYLVANIA

APPARATUS FOR HEATING

Application filed May 31, 1927. Serial No. 195,242.

The present invention relates broadly to the art of metal working, and more particularly as applicable to the heating for reworking or heat treating of metal objects and shapes. More especially, the invention is 5 adaptable to the heat treating of relatively thin shapes of comparatively large dimensions, such for example, as sheets, plates, strips and the like, although the utility of the invention is not limited in this respect.

For purposes of illustration only, the invention will be considered from the standpoint of a heat-treating furnace adaptable for the handling of metal sheets and plates, it 15 being understood that the constructional features of the furnace are such as to adapt it to other uses, and the manner of heating is such as to render it desirable not only for heating for reworking, but for the heat 20 treating of any desired object.

With heat treating surfaces of the character referred to, it is desirable not only to provide a construction capable of operating efficiently from the standpoint of fuel consumption, but also of creating temperature conditions, such that a sheet is subjected on 25 all of its sides and throughout substantially the entire area thereof to substantially uniform temperature conditions at some time 30 prior to its discharge from the furnace. It is further important to provide a furnace structure such that the articles being heated or heat treated are maintained out of contact with surfaces or supports having such temperature characteristics as to mar the 35 surfaces of the articles in contact therewith, or to prevent the obtaining of the desired temperature conditions. It is one of the objects of the present invention to provide a 40 furnace of the general character referred to and capable of efficient operation both from the standpoint of fuel consumption and from the standpoint of the temperature conditions created and maintained therein.

With continuous furnaces, it has been customary to provide conveying mechanism effective for supporting and conveying the sheets through the heat-treating zone. It has frequently been found that such mechanism under the conditions heretofore avail-

able has resulted in the pitting of the sheets at the points of contact between the sheets and the mechanism. We have found that this pitting of the sheets is due to a large extent and almost entirely by reason of the temperature differential between the sheets and such mechanism.

We have further found that in the handling of relatively large sheets, the sheets themselves constitute, in effect, a partition 55 between the source of heat and the mechanism effective in such manner that, during the major portion of the time the furnace is in operation, the mechanism is subjected to temperature produced largely, if not entirely, 60 by radiation from the lower sides of the sheets. Not only is such radiation insufficient to raise the temperature of the mechanism to a temperature equal to that of the main body of the sheets themselves, but it 65 tends to lower the temperature of the sheets on one side in direct proportion to the amount of heat radiated, whereby it has been extremely difficult, if not impossible, to obtain a uniform temperature throughout the 70 same. This temperature differential while substantially negligible with relatively thin sheets by reason of the heat convection characteristics thereof, as well as the intermittent 75 and varied points of contact where the construction of the mechanism is such as to provide a contact of this character, becomes increasingly more marked as the thickness of the sheets is increased. The actual difference 80 in temperature is also dependent upon the character of the mechanism and its mass, as compared to the mass of the sheets. This is particularly true where the mechanism is of 85 such nature that water cooling of the same has been resorted to. Not only is heat radiated downwardly from the sheets to the conveying mechanism, but it is also radiated 90 downwardly to at least certain portions of the bottom of the furnace. In usual furnace structures, the bottom is of considerable mass 95 and consequently capable of absorbing a very substantial amount of heat without being able to effect any return to the sheets of an equivalent amount of heat. The result has been that a temperature differential has exist-

ed between the conveying mechanism and the sheet, such that pitting has been inevitable.

In an effort to overcome the objectionable conditions set forth, furnaces of the so-called muffle type in which muffle flues are provided both above and below the sheets for subjecting the sheets entirely to radiated heat have been proposed. In actual practice, it has been found that the time of treatment may, however, be reduced by the use of heating gases in direct contact with material, and that the cost of producing the desired temperature conditions therein may likewise be reduced where provision is made for direct contact. It is also well known that direct contact provides a more desirable atmosphere from the standpoint of non-oxidation than does a furnace of the muffle type.

The present invention has for one of its objects the provision of a furnace of such construction that where utilized for the heat treating of sheets, successive sheets may be rapidly subjected to the desired temperature conditions in such manner that pitting there-

of is obviated. Another object of the invention is to provide a method suitable for the treatment of sheets and of such nature that not only is the time of treatment reduced, but also that the cost is considerably decreased both by the more effective conservation of heat and the more effective utilization of the heat of the combustion gases.

Still another object of the present invention is to provide a method and apparatus for the heating for reworking or for the heat treating of metal articles, bodies or shapes, such that they are subjected to progressively higher temperatures from the inlet of the furnace to the outlet thereof, whereby the relatively cold entering bodies become effective for absorbing the maximum amount of heat from the waste gases prior to the discharge thereof.

In the accompanying drawings, we have shown for purposes of illustration only, certain preferred embodiments of the present invention, it being understood that the drawings do not define the limits thereof, as changes in the construction and operation may be made without departing either from the spirit of the present invention or the scope of our broader claims.

In the drawings:

Figure 1 is a longitudinal vertical section, partly in elevation and partly broken away, through one form of furnace constructed in accordance with the present invention;

Figure 2 is a transverse sectional view on the line II-II of Figure 1; and

Figure 3 is a view similar to Figure 1, illustrating a slightly modified embodiment of the present invention.

In accordance with the present invention, there may be provided a furnace having any

desired constructional characteristics with respect to the general arrangement, construction and manner of supporting the same, the present invention being adaptable for use with furnaces of different characteristics in this respect. As illustrated herein, the furnace 2 is provided with a suitable charging door 3 controlling the charging opening. Cooperating with the front end of the furnace for delivering material through the charging opening is a suitable approachable and feeding mechanism 4. Cooperating with the discharge opening of the furnace, is a suitable run out table 6. The discharge opening may be controlled in any desired manner, but for purposes which are hereinafter more fully set forth we have found that desirable results may be obtained by the use of an adjustable closure 5.

For effecting movement of the material through the furnace, there may be provided conveying mechanism 7 of any desired construction, such mechanism being herein illustrated as comprising a series of water cooled transversely extending shafts 8 each provided with a series of supporting and conveying disks 9, the disks on adjacent shafts being preferably arranged in staggered relationship. Such shafts may be driven in any desired manner, as for example by the provision of beveled gears 10 thereon cooperating with suitable driving mechanism.

For heating the furnace there may be provided any desired number and arrangement of burners 11 cooperating with the furnace chamber in such manner as to produce a region of highest temperature adjacent the closure 5. The combustion gases are permitted to come into direct contact with the material supported by the conveying mechanism in such manner as to directly envelop the same. Where, however, sheets are being conveyed, it has been found that such sheets have heretofore prevented the maintaining of conditions effective for the desired temperature both in the conveying mechanism and throughout the entire area of the sheets. As previously pointed out we have found that this is due in large measure to the tendency of the sheets to radiate heat downwardly without the provision of any means for restoring or renewing the heat thus lost.

In accordance with one feature of the present invention, we may provide the floor of the furnace with a series of flues 12 extending longitudinally thereof. At one end the flues are adapted to receive heating gases directly from the furnace chamber as will be clearly apparent from Figure 1 of the drawings while at the opposite end they discharge into a stack flue 13 leading to the stack 14. While the flues may be of any desired construction, we have found that the most advantageous results are obtained by the provision of a flue structure such that a temperature condition

in the furnace chamber below the sheets, in the conveying mechanism and in the furnace floor, substantially equal to the temperature in the main portion of the furnace chamber, 5 may be maintained. To this end, the flues are conveniently constructed of material having a high heat transfer coefficient and preferably of relatively light mass at least at that portion representing the division between the furnace chamber and the flue.

With a construction of the general character referred to, sheets admitted to the furnace through the charging opening and passed therethrough are subjected to progressively increasing temperatures. Adjacent the charging end of the furnace, the relatively cold sheets are effective for absorbing the maximum amount of heat from the waste gases, whereby heat conservation is effected.

As the sheets approach the discharge end of the furnace, they are brought into a temperature zone of substantially uniform characteristics throughout. The heat radiated upwardly to the conveying mechanism and to the sheets by the flues 12 maintains that portion of the conveying mechanism which comes into contact with the sheets at a temperature substantially equal to the temperature in the sheets themselves. This temperature equilibrium between the sheets and the conveying mechanism obviates the objectionable pitting which has heretofore resulted.

By the utilization of an adjustable closure 5 for the discharge opening, in combination with the adjustable closure 3 for the charging opening it will be apparent that the pressure conditions within the furnace chamber may be varied at will. By restricting the flow through these openings, a relatively higher pressure resulting in the passage of a greater proportion of the gases through the flues will be established, while by adjusting the closures in such manner that a relatively freer flow of gases directly from the chamber is permitted, 40 a proportionately smaller flow through the flues may be obtained. The adjustable closures in addition to regulating the pressure within the furnace and the flow of combustion products through the flues, likewise determine the character of the atmosphere within the furnace and the frequency of complete renewal of such atmosphere.

The construction also lends itself admirably to conveying mechanism of the water cooled type, thereby enabling the use of material of a relatively inexpensive nature in contrast to the more expensive materials required where water cooling is not employed. In other words, the utilization of flues having the characteristics referred to, results in the creation of a temperature condition immediately above the same which is substantially the same as the temperature condition in any other part of the furnace, irrespective of the 55 presence or absence of a sheet or sheets with-

in the furnace. Consequently, they are effective for maintaining a temperature in the portions of the conveying mechanism which contact with the sheets, which is substantially equal to and preferably as high as or higher than the temperature of the sheets themselves. This temperature condition while of relatively minor importance adjacent the charging end of the furnace, is of utmost importance in the zone or zones of higher temperature in the furnace, in which zones uniformity of temperature throughout the material being heated for reworking or heat treated is both desirable and essential.

In Figure 3, there is illustrated a slightly modified embodiment of our invention, in which we have indicated flues 12' so disposed as to lie closely adjacent the under side of the material M being treated and between the supporting parts of the conveying mechanism 7'. In this position, they are directly effective on the supporting portions of the conveying mechanism and on the lower surfaces of the material whereby radiation or convection of heat from such material to the conveying mechanism or to the bottom of the furnace is prevented.

It will be apparent to those skilled in the art that the present invention involves an operation either in connection with the heating for reworking or the heat treating of material which represents a fundamental advance in the art. Such advance is obtained by reason of the creation of temperature zones such that uniform temperature conditions throughout an entire body of material are obtainable in the zone or zones of higher temperature within the furnace, such conditions being obtained with the use of a conveying mechanism the supporting portions of which are kept at all times at a temperature such that pitting of the surfaces with which they come into contact is obviated. Our invention, therefore, is limited only to the construction of a furnace such that the desired temperature conditions at a predetermined zone or zones may be obtained and maintained irrespective of the constructional features provided for effecting the same. More particularly our invention is predicated on the realization of the cause of pitting in material such as sheets and in the maintaining of temperature conditions such that pitting is prevented, together with the obtaining of uniform temperature conditions throughout the material itself.

The term heating as hereinafter utilized in the claims is used in its generic sense as definitive of an operation having for its purposes either a heat treating or a heating for reworking.

We claim:

1. In a heating furnace having a heating chamber, conveying means therein, burners for supplying products of combustion to said

chamber, and indirect heating means intermediate the supporting plane of said conveying means and the main furnace bottom receiving and conveying such products of combustion and serving to heat said conveying means and prevent radiation of heat downwardly from material thereon.

- 5 2. In a heating furnace having a heating chamber, conveying means therein, burners for supplying products of combustion to said chamber, and indirect heating means intermediate the supporting plane of said conveying means and the main furnace bottom, said indirect heating means comprising a plurality of flues adapted to receive and convey such products of combustion from said chamber and serving to heat said conveying means and prevent radiation of heat downwardly from material thereon.
- 10 3. In a heating furnace having a heating chamber, conveying means therein, burners for supplying products of combustion to said chamber, and indirect heating means intermediate the supporting plane of said conveying means and the main furnace bottom receiving its heating medium from said chamber adjacent the discharge end thereof receiving and conveying such products of combustion and serving to heat said conveying means and prevent radiation of heat downwardly from material thereon.
- 15 20 30

In testimony whereof we have hereunto set our hands.

EDWARD M. FREELAND.
